UNITED STATES PATENT OFFICE.

ROBERT MAW, OF MONTREAL, QUEBEC, CANADA, ASSIGNOR TO THE UNIVERSAL MACHINERY COMPANY LIMITED, OF MONTREAL, CANADA.

REVERSIBLE-FLOW PUMP.

1,330,889.

Specification of Letters Patent. Patented Feb. 17, 1920.

Application filed February 20, 1917, Serial No. 149,826. Renewed June 11, 1919. Serial No. 303,477.

To all whom it may concern:

Be it known that I, ROBERT MAW, a subject of the King of Great Britain, and resident of the city of Montreal, in the Province 5 of Quebec and Dominion of Canada, have invented certain new and useful Improvements in Reversible-Flow Pumps, of which the following is a full, clear, and exact description.

10 This invention relates to improvements in reversible flow pumps, and the object of the invention is to provide a pump adapted to circulate a transmission liquid in either positive or reverse direction without altering the 15 direction of revolution of the pump.

A further object is to provide a pump which will circulate the liquid in either direction with equal facility and efficiency and without producing any frothing.

20 In apparatus such as described in the specification filed by myself and W. B. McLean under Serial Number 112,449, and as described in my co-pending application, Serial Number 149,827, a reversible pump is 25 shown. That is to say, the actual mechanical features of the pump are such that the direction of flow of the oil may be reversed. In practice, however, the pumps as shown are not efficient, if the reversing is frequent, 30 for the reason that the oil becomes filled with air and churned to a froth. In my co-pending application, I have disclosed means for separating the air from the oil and eliminating this froth, but the apparatus shown 35 is intended for operation principally in one direction, as in the case of an automobile, and in spite of the air separating means would not be properly efficient, where reversing was frequent, such as would occur if 40 the pump were used to supply oil to a motor running a plate rolling machine or the like. The reason for this is that the separating chamber is too large, and contains too much space for an air cushion, so that too much 45 time is lost in filling this chamber before the oil can reverse its flow as regards the utilizing device.

To overcome this condition, I divide the separation chamber into two parts and 50 slightly alter the arrangement of suction, discharge and return passages from that shown in my co-pending case, with the result that the pump draws oil from one chamber and discharges it into the other chamber, from which it flows to the motor or

other utilizing device, this chamber being kept full. The oil returned from the motor flows into the chamber where the separation takes place. When the pump is reversed, the conditions in the chambers reverse. In 55 this way, the amount of air space is reduced, and the reversing more quickly effected. Each chamber is provided with an air outlet valve.

In the drawings which illustrate the invention:—

Figure 1 is a diagrammatic elevation of the device with part of the casing broken away.

Fig. 2 is a section on the line 2—2, Fig. 1.

Referring more particularly to the drawings, 11 designates a pump having an extension 12 of the casing divided by a partition 13 into two entirely separate chambers 14 and 15. Passages 16, 17, 18 and 19 are 70 provided. The passages 16 and 17 connect the pump with the chambers 14 and 15, and the passages 18 and 19 connect the chambers 15 and 14 with the motor 20. When the pump is operated, it draws oil through the 75 passage 16 from a point near the bottom of the chamber 14, and discharges it through the passage 17 into the chamber 15. From the chamber 15, the oil flows through the 80 passage 18 to the motor 20. After passing 85 through the motor, the oil returns through the passage 19 into the chamber 14 at a point near the bottom thereof and contiguous to the inlet of the passage 16. In this operation, the chamber 15 is maintained full 90 of oil and the pressure of the oil holds the air escape valve 22 closed. The oil level in the chamber 14 is somewhat below the top of the chamber, so that the valve 21, which is normally open, permits air separating from 95 the oil to escape. When the pump is operated to reverse the flow of oil, it draws oil from the chamber 15 through the passage 17, and discharges it into the chamber 14 through the passage 16. This discharge of 100 oil almost instantly fills the chamber 14 and closes the valve 21, the oil thus accumulated being drawn from the chamber 15, so that the valve 22 is allowed to open. As soon as the chamber 14 is full, the oil flows through 105 the passage 19 to the motor 20 and returns from the motor through the passage 18 to the chamber 15, where any air which has gotten into the motor separates from the oil and escapes through the valve 22.

The great advantage of this arrangement is that the volume of air space is reduced, and on whichever side the pressure exists, the chamber is completely filled with purely liquid oil.

Having thus described my invention, what I claim is:—

1. In a device of the character described, the combination with a pump and a motor, 10 of an oil receptacle divided into two isolated chambers, a passage from each chamber connected to the pump and a passage from each chamber connected to the motor.

2. In a device of the character described, 15 the combination with a pump and a motor, of a receptacle intermediate the pump and motor divided into two isolated chambers, a passage leading from near the bottom of each chamber to the pump, and a pas-

sage leading from near the bottom of each 20 chamber to the motor, and a normally open valve in each chamber closable by accumulation of oil in the chamber.

3. In a fluid transmission system, a pump and a motor, a transmission fluid receptacle 25 intermediate the pump and motor divided into two isolated chambers, a normally open air vent in each chamber, means whereby the pump will draw liquid from one chamber and completely fill the other chamber 30 closing the valve thereof, and means whereby oil forced into said second chamber will flow to the motor and return from the motor to the first chamber.

In witness whereof, I have hereunto set 35 my hand.

ROBERT MAW.
